Primary Examiner — Leanne Was-Englehart*Assistant Examiner* — Justin A Johnson(74) *Attorney, Agent, or Firm* — LEGALFORCE RAPC
WORLDWIDE(57) **CLAIM**

The ornamental design for a bicycle helmet with LED light, as shown and described.

DESCRIPTION

FIG. 1 is a front top-right side perspective view for a bicycle helmet with LED light, showing my new design;

FIG. 2 is a front elevational view of FIG. 1 thereof;

FIG. 3 is a rear elevational view of FIG. 1 thereof;

FIG. 4 is a left side elevational view of FIG. 1 thereof;

FIG. 5 is a right side elevational view of FIG. 1 thereof; and,
FIG. 6 is a top plan view of FIG. 1 thereof.

The broken lines indicate unclaimed portions of the bicycle helmet with LED light and form no part of the claimed design.

1 Claim, 6 Drawing Sheets(56)
